CLAIM

The ornamental design for a modular spacecraft bus system, as shown and described.

DESCRIPTION

FIG. 1 is a front view of the modular spacecraft bus system showing our new design;

FIG. 2 is a front exploded view of the modular spacecraft bus system of FIG. 1;

FIG. 3 is a rear view of the modular spacecraft bus system of FIG. 1;

FIG. 4 is a top view of the modular spacecraft bus system of FIG. 1;

FIG. 5 is a bottom view of the modular spacecraft bus system of FIG. 1;

FIG. 6 is a left view of the modular spacecraft bus system of FIG. 1;

FIG. 7 is a right view of the modular spacecraft bus system of FIG. 1;

FIG. 8 is a top perspective view of the modular spacecraft bus system of FIG. 1; and,

FIG. 9 is a bottom perspective view of the modular spacecraft bus system of FIG. 1.

In FIGS. 1–9, broken lines indicate portions of the modular spacecraft bus system that form no part of the claimed design.

1 Claim, 9 Drawing Sheets
